E. P. RICH,
COMPOUND VALVE,
APPLICATION FILED MAR. 20, 1920.

1,428,254.

Patented Sept. 5, 1922.

UNITED STATES PATENT OFFICE.

EDWARD P. RICH, OF CHICAGO, ILLINOIS.

COMPOUND VALVE.

Original application filed January 30, 1919, Serial No. 274,007. Divided and this application filed March 20, 1920. Serial No. 367,549.

To all whom it may concern:

Be it known that I, EDWARD P. RICH, a citizen of the United States, residing at Chicago, in the county of Cook and State of Illinois, have invented a certain new and useful Improvement in Compound Valves, of which the following is a specification.

My invention relates to compound valves and is applicable more particularly to steam pipes in which the source is higher than the valve and freezing is apt to occur in case condensation should collect when the valve is closed. My device is of special value in steam heating systems where, as in some manufacturing and commercial installations, the steam supply pipes are overhead, or at least at a higher level than the radiator. An installation of this type is described and claimed in my co-pending application for a heating system, Serial No. 274,007, filed January 30, 1919, now patent number 1,338,961, of which this present application is a division. As pointed out in said co-pending application, when the steam supply is above the radiator, when ordinary valves are used, condensed steam collects at the valve and is very apt to freeze and cause trouble in cold weather if the radiator is installed in a place where the temperature is allowed to drop at night or on Sundays or holidays. The object of my invention is to provide a compound valve so constructed that it will require no attention whatever except when it is desired to regulate the temperature of the radiator. In other words, with my device neglect on the part of the attendant will have no bad consequences and the device will never have to be touched except when it is desired to turn the heat on in the radiator or to shut it off.

A contributory object is to provide a valve having a main duct controlled by a manually operated valve and automatic, thermally controlled means subject to the heat of the fluid on the inlet side of the main valve for retaining steam and releasing, into the main duct, the liquid of condensation. A further contributory object is to employ, as the thermally controlled means, a bypass valve actuated by a thermo-sensitive element which is on the inlet side of said bypass valve and located in a chamber which

is in direct and permanent communication with the main duct on the inlet side of the main valve.

I accomplish my object by the mechanism illustrated in the accompanying drawing in which—

Figure 1 is a vertical sectional assembly view taken on the line 1—1 Figure 2.

Figure 2 is a view partly in vertical section taken on the line 2—2 Figure 1 and

Figure 3 is a plan section taken on the line 3—3 Fig. 1.

Figure 4 is a sectional view on the line 4—4 Figure 1.

Like numerals denote like parts throughout the several views.

In the drawings, 7 represents a valve casing provided in the present case with an internally threaded hub 8 adapted to be connected to the source of steam supply, as for example, a "drop riser" leading from an overhead source. My device is not reversible, inlet for outlet, and the hub 8 is located at the inlet end. Within the valve casing is an internal wall 12 having an annular opening at the top, into which screws a valve seat 13 adapted to co-operate with the main shut off valve 14 which is here shown as being arranged horizontally. It will be understood, however, that any of the well known types of shut off valves may be employed with like effect. It will be understood also, that in some cases the ring 13 may be omitted, permitting the main valve to seat upon one of the integral portions of the casing.

Valve 14 is controlled by a threaded stem 15 passing through a suitable stuffing box composed of the parts 16, 17 and 18 or any suitable substitute therefor. A hand wheel 20 is provided for rotating the stem. At the outlet end of the valve casing is an internally threaded hub 22 adapted to be connected to the radiator (not shown).

At the side of the valve casing, opposite to the internal wall 12, is a by-pass having two principal chambers 25 and 26. These are separated by a wall 27 at the upper end of which is an annular opening supporting a valve seat 30. This is adapted to co-operate with the valve proper 31 of a thermal expansion trap, having a so-called "bellows" 32 sus-

pended from a cap 33 screwing down into the top of the by pass. Traps of this kind are well known and for the present purpose it is sufficient to say that the device is 5 so constructed that beneath the pre-determined critical temperature the bellows will remain contracted and hold the valve 31 away from its seat. When the critical temperature is reached or exceeded the bellows 10 expands and lowers the valve on its seat, thus shutting off the passage way. In my device I so arrange and construct the thermal trap that the valve 31 will remain open unless subjected to the temperature of steam. 15 Consequently, the valve will remain open and permit water to pass but will close as soon as it becomes enveloped in steam. By preference the by-pass 25, 26 is in semicircular form when viewed in plan as in Figure 20 3. By preference it is also located at or near the bottom of the valve casing.

In practice, the device is and must be installed in such manner that the hub 8 is at the inlet end and hub 22 at the outlet end. 25 Ordinarily, moreover, the axis of the hub 8 will be in line with the axis of the hub 22 and these axes will be installed in horizontal position. In operation, when the apparatus is installed in the manner described, if the 30 main valve 14 is open the steam will have a practically unobstructed flow through the valve casing and into the radiator. If the heat of the radiator is not required, the attendant closes the main valve. So long as 35 the internal parts of the valve casing remain above the boiling point of water, the thermal valve 31 will remain closed. As the parts cool off, however, especially in the supply pipes, water will begin to collect in the bottom of the valve casing. As soon as this reaches the bellows the latter will contract 40 and open valve 31 and permit the water to pass off through the passage 26 and into the outlet 24. As soon as the water has passed 45 and steam commences to flow, the bellows will immediately close the valve. Consequently, the piping above the valve casing will be kept free of water and at the same time no appreciable amount of steam will be 50 permitted to enter the radiator. Thus the radiator will be kept cold and at the same time it and the pipes leading to it will be kept clear of water. As a result, the attendant will have the same control over the 55 radiator that he would have with an ordinary valve, but he is relieved of the necessity of watching to see that water does not collect. Ordinarily, in freezing weather, it would be necessary for him to open the main 60 valve from time to time to prevent danger of freezing, but by installing my apparatus no attention is necessary.

It will be observed that in my device the automatic valve, or at least the thermosensitive element which controls it, is on the sup-

ply side of the main valve—that is, it is subject to the action of the fluid on the supply side whether the main valve is open or closed. It will also be noted that the wall 27 and the valve 30 are at a lower level than the top of 70 the inlet opening 8. This positively prevents the collection of water and the formation of ice in sufficient quantity to obstruct the flow through the main valve. In other words, by employing my device, even when installed in a system in which the steam supply pipes come from a higher level, and even though the main valve be left shut for days at a time, a sudden freezing spell will have no injurious effect either on my device or the 75 system with which it is connected; for the simple act of opening the main shut off valve will instantly enable the steam to flow through.

Having thus described my invention, what 80 I claim as new and desire to secure by Letters Patent is:

1. A device of the class described having a valve casing provided with a main shutoff valve, a by-pass around said valve, an automatic valve in said by-pass, and a thermosensitive element adapted to control said automatic valve, said thermosensitive element being located on the supply side of said valves, whereby it is at all times subject to 90 the temperature of the fluid entering the device. 95

2. A device of the class described having a valve casing provided with a main shut off valve, a by-pass around said valve, an automatic valve in said by-pass, located at a point beneath the level of the main valve, and a thermosensitive element adapted to control said automatic valve, said thermosensitive element being located on the inlet side of the 100 automatic valve. 105

3. In combination, a valve casing having a partition with two openings in it, a main shut off valve for controlling one of said openings, and a thermally controlled valve 110 for controlling the other of said openings, the thermo-sensitive element of the thermally controlled valve being in position to be at all times exposed to the action of the fluid on the inlet side of the partition. 115

4. In combination, a valve having a valve casing provided with an internal partition having two openings in it, a main shut off valve for controlling one of said openings, and a thermally controlled valve for controlling the other of said openings, the thermosensitive element of the thermally controlled valve being located on the supply side of said partition whereby it is at all times exposed to the action of the fluid on 120 the inlet side of the partition. 125

5. In a device of the class described, the combination of a casing having a wall therein dividing the casing into two compartments, said wall having a passage through 130

it surrounded by a valve seat, a main shut off valve cooperating with said valve seat, a duct passing horizontally around said wall and forming a by-pass, said by-pass having 5 a wall dividing it into two compartments, and the latter wall having a passage through it surrounded by a valve seat, an automatic valve for controlling the latter valve seat, and a thermoresponsive element adapted to control said automatic valve and being located on the supply side thereof.

In witness whereof, I have hereunto subscribed my name.

EDWARD P. RICH.
